UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKING APPARATUS

Application filed March 25, 1930. Serial No. 438,751.

My invention relates to railway braking apparatus, and particularly to braking apparatus of the type comprising braking bars located in the trackway adjacent a track rail and arranged to be moved at times into engagement with the wheels of a car or vehicle.

I will describe one form of braking apparatus embodying my invention, and will then point out the novel features thereof in the 10 claim.

In the accompanying drawing, Fig. 1 is a top plan view showing one rail of a railway track having associated therewith one form of braking apparatus embodying my invention. Fig. 15 2 is a transverse sectional view of the braking apparatus illustrated in Fig. 1 showing on a somewhat larger scale the positions which the parts occupy when the braking apparatus is engaging a car wheel. Fig. 20 3 is an enlarged detail view of a portion of the apparatus illustrated in Fig. 1.

Similar reference characters refer to similar parts in all three views.

Referring first to Figs. 1 and 2, the reference character 1 designates a railway track rail which is supported by tie plates 2 secured to the usual cross ties 3, and along which cars normally move in the direction indicated by the arrow. Located on opposite sides of this rail are two braking bars B and C, each comprising a plurality of beam sections 6. Each beam section 6 is provided with the usual wheel engaging shoe 7. Pivotally supported in the trackway adjacent each beam section 6 of each braking bar are a plurality of trunnions D. Each trunnion D is connected with the adjacent beam section by means of a resilient link G, the links G being disposed at angles with the rail in such manner that movement of the beam sections in directions parallel to the track rail will result in movement of these sections toward and away from the rail, that is, into closed and open positions of the braking bars.

45 The beam sections may be moved in directions parallel to the rail by any suitable means, such, for example, as by the mechanism shown and described in my copending application for Letters Patent of the United States, Serial No. 307,895, filed September 24,

1928, for railway braking apparatus, which has become Patent No. 1,812,191. This operating mechanism is omitted from the drawing because it forms no part of my present invention. It should be pointed out, however, that this mechanism is so constructed that when the braking bars are in their closed positions and a beam section is engaging a car wheel, thereby causing the springs of the resilient links G which are connected with 55 such beam section to become compressed, a limited amount of tipping of this beam section will take place as illustrated in Fig. 2, this tipping causing the associated brake shoe to engage the car wheel at a higher point and 60 therefore a more effective point than would be the case if this tipping did not take place.

Referring now also to Fig. 3, each beam section 6 is provided at one end with a vertical tongue 8 which enters a vertical groove 9 in the confronting end of the adjacent beam section. With this articulated connection, car wheels may pass smoothly from one beam section to the next without undesirable 65 shocks. The parts are so arranged that the 70 tongues 8 are on the entering ends of the beam sections, so that when a car wheel passes from one beam section to the next, the wall 9a of the corresponding groove 9 which is closest to the rail 1 will engage the side 8a of 75 the tongue on the beam section next in advance. The parts are further proportioned 80 in such manner that the regions of contact between the mating tongues and grooves under the above conditions are at least as 85 close to the rail as the line through the points of connection between the beam sections and the resilient links G.

With the parts constructed in this manner, I have found that when the braking bars are in their closed positions and a car wheel is about to pass from a given beam section to the beam section next in advance, the entering end of the beam section next in advance 90 will not only be forced away from the rail the same distance as the leaving end of the given beam section, but will also be tipped or raised approximately the same amount as the given beam section is raised by engagement with the car wheel. As a result, when 95 100

the car wheels pass from one beam section to the next, there is no shock either to the car wheels or to the braking apparatus so that a more effective braking action takes place, and the life of the apparatus is greatly lengthened due to the decreased strains. Furthermore, since the beam sections are raised as well as moved away from the rail in advance of the entry of a car wheel into a section, any tendency of the beam sections to lift the car wheels off of the rails as the wheels enter a section is practically eliminated.

Although I have herein shown and described only one form of railway braking apparatus embodying my invention, it is understood that various changes and modifications may be made therein within the scope of the appended claim without departing from the spirit and scope of my invention.

Having thus described my invention, what I claim is:

Railway braking apparatus comprising two beam sections located end to end beside a track rail, a plurality of resilient links connected at one end with each beam section in such manner that said beam sections will be moved toward or away from the track rail into open or closed positions in response to movement of the beam sections in directions parallel to the rail and that when said beam sections are in their closed positions and a beam section is engaging a car wheel a slight amount of tipping of such beam section takes place, the rear one of said beam sections being formed on its leaving end with a vertical groove having one wall at least as close to the rail as the line of application of forces applied to the beam sections by said resilient links, and a tongue on the other beam section entering said groove and adapted to be engaged by said wall when said rear beam section is engaging a car wheel, whereby said other beam section is both moved away from the rail and tipped in advance of the entry of the car wheel into said other section.

In testimony whereof I affix my signature.

HERBERT L. BONE.
